UNITED STATES PATENT OFFICE.

CORYDON H. WILMOTH, OF TERRE HAUTE, INDIANA.

RATCHET DRILL-STOCK.

SPECIFICATION forming part of Letters Patent No. 365,214, dated June 21, 1887.

Application filed February 28, 1887. Serial No. 219,142. (No model.)

To all whom it may concern:

Be it known that I, CORYDON H. WILMOTH, a citizen of the United States, residing at Terre Haute, in the county of Vigo and State of Indiana, have invented a new and useful Improvement in Ratchet Drill-Stocks, of which the following is a specification.

My invention relates to an improvement in ratchet drill-stocks. In this class of drill-stocks as heretofore constructed the drill-holder is provided with a ratchet-wheel which is engaged by a pawl mounted on a lever, and the drill-holder is turned by the movement of the lever in one direction only.

15 The objects of my improvement are to cause both the forward and backward movement of the lever to rotate the drill-holder constantly in one direction, and to provide convenient means for feeding the drill to the work.

20 The accompanying drawings illustrate my invention.

Figure 1 is a plan. Fig. 2 is a vertical section. Fig. 3 is a partial transverse section at *a*, Fig. 2. Fig. 4 is a partial transverse section at *b*, Fig. 2.

25 The drill-holder consists of a short cylindrical shaft, *A*, having a socket, *c*, to receive the drill-shank, and two ratchet-wheels, *d* and *e*, secured thereon.

30 *B* is the handle having bearings *f* and *g*, in which shaft *A* revolves.

35 *C* is the operating-lever, mounted on the upper portion of shaft *A* so as to turn thereon, embracing the ratchet-wheel *d* and carrying the pawl *h*, which engages wheel *d*.

40 *D* is a collar mounted on shaft *A*, so as to turn thereon between the bearings *f* and *g*.

45 *E* is a cog-wheel, also mounted so as to turn on the shaft, and secured to collar *D* so as to turn therewith. A pawl, *i*, pivoted to collar *D*, engages the ratchet-wheel *e*. Pivoted to handle *B* is a lever, *F*. One end of lever *F* forms a cogged segment which engages wheel *E*, and the other end of the lever is connected with the free end of the operating-lever by a screw, *j*, which passes through a slot, *k*, in the lever *F*.

50 *H* is the ordinary screw-socket for feeding the drill, the upper end of the screw *I* being adapted to engage the usual clamping-bar,

(not shown,) so as to remain stationary while the socket is turned.

For the purpose of enabling the operator to conveniently turn socket *H* at will, and thereby force the drill-stock and drill downward, 55 socket *H* is provided with teeth *l*, and a sliding clutch, *m*, is mounted on the operating-lever.

Clutch *m* is held normally out of engagement with socket *H* by a spring, *n*, and is forced into 60 engagement with the socket by means of a bent lever, *o*, arranged under the handle of the operating-lever.

In operation, the drill-stock carrying a drill and being clamped to the piece to be drilled 65 by the clamping-bar engaging the upper end of the feed-screw in the usual well-known manner, the operator holds handle *B* in the left hand and swings the operating-handle back and forth with the right hand. When the operating-lever is swung toward the left, pawl *h* engages wheel *d* and turns the drill in the same direction in which the lever is moving.

When the operating-lever is swung toward the right, lever *F*, moving in the same direction, 75 turns wheel *E* and collar *D* in the opposite direction to that in which the operating-lever is moving, and pawl *i*, engaging ratchet-wheel *e*, the drill is turned in the same direction. Both movements of the operating-lever thus 80 turn the drill in the same direction. When

the operator wishes to feed the drill to the work, he raises the free arm of bent lever *o* with one finger of the hand holding the operating-lever, and thereby forces clutch *m* into 85 engagement with teeth *l* on socket *H*, and the socket then turns with the lever until lever *o* is released.

85 I claim as my invention—
1. In a ratchet drill-stock, the combination, 90 with the tool-holder, the ratchet-wheel *d*, the operating-lever, and the pawl pivoted to the lever and arranged to engage the ratchet-wheel, of the ratchet-wheel *e*, collar *D*, pawl *i*, cog-wheel *E*, and lever *F*, all arranged to co-operate substantially as shown and described, for the purpose specified.

95 2. In a ratchet drill-stock, the combination of a shaft having a socket adapted to hold a tool, two ratchet-wheels secured to said shaft, 100

an operating-lever pivoted on said shaft, a pawl pivoted to said operating-lever and arranged to engage and turn one of said ratchet-wheels when the lever is turned in one direction only, a collar mounted so as to turn on the shaft, a pawl pivoted to said collar and arranged to engage and turn the other of said ratchet-wheels, and intermediate connecting mechanism connecting said collar and the op-

erating-lever, whereby the second ratchet-wheel to and the shaft are turned in the same direction as at first during the return movement of the operating-lever, substantially as specified.

CORYDON H. WILMOTH.
